BOLT OPERATING MECHANISM FOR
MACHINE GUNS

Samuel G. Green, Gray, Ga.

Application October 11, 1935, Serial No. 44,572

4 Claims. (Cl. 89—27)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a bolt operating mechanism for machine guns.

Machine guns are provided with a breech bolt handle to permit manual retraction of the bolt in order to reproduce the action of the gun mechanism during firing for the purpose of initially loading the gun and correcting stoppages. The reciprocation of the bolt handle during firing of the gun has frequently caused injury to members of the gun crew. In the heavy 15 machine gun such as the .50 caliber, a considerable effort is required to initiate retraction of the bolt and in performing this operation the gunner's hand is frequently injured.

The purpose of this invention is to facilitate 20 manual retraction of the breech bolt and to this end the bolt handle is arranged to have an initial lever action. The handle is also arranged so that it is not retracted by the breech bolt during firing of the gun.

25 With the foregoing and other object in view, the invention resides in the novel arrangement and combination of parts and in the details of construction hereinafter described and claimed, it being understood that changes in the precise 30 embodiment of the invention herein disclosed may be made within the scope of what is claimed without departing from the spirit of the invention.

A practical embodiment of the invention is 35 illustrated in the accompanying drawing, wherein:

Fig. 1 is a plan view of a machine gun equipped with the improved bolt operating mechanism.

Fig. 2 is a view in side elevation.

40 Fig. 3 is a sectional view on the line 3—3 of Fig. 2.

Fig. 4 is a plan view of the slide.

Fig. 5 is a view in side elevation thereof.

45 Referring to the drawing by characters of reference, there is shown the breech casing 5 of a machine gun having a side plate 6 with a longitudinally extending slot 7 in which the stud 8 of a breech bolt 9 reciprocates during actuation of the gun. A frame 10 having a slot 11 correspond- 50 ing to, but wider than the slot 7, and in alignment therewith, is attached to the outside of the side plate by a plurality of screws or bolts 12.

The slot 11 in the frame extends forwardly 55 beyond the front end of the slot 7 to accommo- date a slide 13 which is disposed in front of the

stud 8 of the breech bolt when the breech bolt is in its extreme forward or "in battery" position. The slide is provided on its upper and lower sides with tongues 14—14 which ride in grooves 15—15 formed between the rail portions of the frame 5 and the side plate 6. The rear face of the slide is formed with a semi-circular recess 16 for engaging the stud 8 of the breech bolt.

A lever 17 having a heel 18 and a toe 19, is 10 pivotally mounted between the heel and toe on a stud bolt 20 which is threaded in the slide. The lever is laterally confined between a collar 21 and a nut 22 on the bolt 20 and a torsion spring 23 embracing the collar has one end attached to the collar and the other end to the lever. A 15 stop pin 24 is carried by the slide forwardly of the bolt 20 in position to engage the under side of the heel 18 of the lever when the lever is in an upright vertical position where it has been moved and is held by the spring 23. 20

A stud bolt 25 is threaded in the frame 10 and is positioned directly underneath the bolt 20 when the slide carrying the bolt 20 is in the forward position. The bolt 25 preferably carries a roller 26 which is adapted to engage the under side of 25 the toe 19.

The upper end of the lever carries a laterally 30 projecting handle 27 which is adapted to be grasped by the gunner and acted on to retract the slide.

A plunger 28 is carried by the frame and is 35 normally urged by a spring 29 into the path of movement of the slide. When the slide is in its foremost position the beveled or pointed end 30 of the plunger engages in a recess 31 in the slide. 35

In the normal position of the parts the breech bolt 9 is in battery and the slide 13 is at the forward end of the frame where it is releasably held against retraction by the plunger 28 and positively held against forward displacement by virtue 40 of the engagement of the toe 19 of the lever with the roller 26, the lever being limited to an upright vertical position because of the engagement of its heel 18 with the stop pin 24. The slide and lever remain in this position when the breech bolt reciprocates in automatic operation of the gun. 45

When it is desired to manually retract the breech bolt, the handle 27 is grasped by the gunner and a rearward pull is exerted. This 50 action produces rotation of the lever 17 about its pivot 20 and since the toe of the lever is fulcrumed on the roller 26, the pivot, and the slide 13 to which it is secured, are displaced rearwardly. The slide being connected to the breech bolt 55

through the stud 8 therefore produces retraction of the breech bolt. The lever action serves to smoothly initiate retraction of the breech bolt which at this time is being unlocked with respect to the barrel.

When the lever and slide are retracted a distance sufficient for the toe 18 to clear the roller, the effort exerted on the handle causes the lever to be rotated about its pivot until the toe engages the stop pin 24 of the slide 13. The lever is now in position parallel to and in line with the slide 13 so that the pull on the lever is directly transmitted to the slide.

When the slide is fully retracted as shown in dotted lines in Fig. 2 the lever is released. The breech bolt is now free to be returned into battery by its return spring which was energized upon retraction of the breech bolt. The stud 8 of the breech bolt being in rear of the slide causes the slide to be driven forwardly. As soon as the lever is released, the torsion spring 23 restores it to the upright position where the heel 18 engages the stop pin 24. The slide is arrested in its forward movement when the toe 18 of the lever engages the roller 26.

I claim:

1. In a machine gun, a casing having a side plate provided with a slot, a breech bolt reciprocally mounted in the casing and having a stud extending through the slot, a frame on the outer side of the side plate, a slide reciprocally mounted in the frame and engaging the forward face of the stud on the bolt, a lever having a toe and a heel and pivotally mounted on the slide between the toe and heel, a stop pin carried by the slide in front of the pivot of the lever, a spring normally acting to rotate the lever to a vertical position with its heel engaging the stop pin, and a member serving both as a fulcrum and a stop carried by the frame below the pivot of the lever.

carried by the frame below the pivot of the lever and engageable by the toe of the lever.

2. In a machine gun, a support, a breech bolt reciprocally mounted in the support and having a projecting member, a slide reciprocally mounted on the support and engageable with the front face of the projecting member of the breech bolt, a lever having a toe and a heel and pivotally mounted on the slide between the toe and heel, a stop pin carried by the slide in front of the pivot of the lever, a spring normally acting to rotate the lever to a vertical position with its heel engaging the stop pin, and a member serving as a fulcrum and a stop carried by the support below the pivot of the lever.

3. In a machine gun, a support, a breech bolt reciprocally mounted in the support and having a projecting member, a slide reciprocally mounted on the support and engageable with the front face of the projecting member of the breech bolt, a lever having a toe and a heel and pivotally mounted on the slide in front of the bolt element and between the toe and heel, a stop pin carried by the slide in front of the pivot of the lever, and a member serving as a fulcrum and a stop carried by the support below the pivot of the lever.

4. In a machine gun, a support, a breech bolt reciprocally mounted in the support and having a projecting member, a slide reciprocally mounted on the support and engageable with the projecting member of the breech bolt, a lever pivotally mounted on the slide in front of the bolt element, a stop pin carried by the slide in front of the pivot of the lever, and a member serving as a fulcrum and a stop carried by the support below the pivot of the lever.

SAMUEL G. GREEN.
